UNITED STATES PATENT OFFICE.

MATTHEW MAYER, OF MANSFIELD, OHIO, ASSIGNOR TO CHARLES M. WALTER.

BOWDEN CONTROLLING MECHANISM.

Application filed May 2, 1924. Serial No. 710,687.

To all whom it may concern:

Be it known that I, MATTHEW MAYER, a citizen of the United States, residing at Mansfield, in the county of Richland and State of Ohio, have invented certain new and useful Improvements in Bowden Controlling Mechanisms, of which the following is a specification.

My invention relates to Bowden controlling mechanisms, and particularly controlling mechanisms adaptable for use in connection with a "shut-off" valve installed in the supply line for gasoline to an automobile engine, although obviously, it is not limited to such a use.

An object of my invention is to produce such a mechanism operable by a simple "push" and "pull" Bowden wire with a suitable controlling handle therefor, and which will, when set to either extreme position, remain in such a position regardless of the vibrations of the vehicle.

Another object is to provide such a mechanism which will be positive in operation and which by its characteristic designing, indicates to the operator while being operated the position of the valve controlled thereby.

Other objects of my invention and the invention itself will be apparent from the drawings forming a part of this specification.

Referring now to the drawings:—

Fig. 1 shows a side elevation of an embodiment of my invention, the manually operable portion being shown in isometric view, however, the apparatus being shown in one of the valve extreme positions.

Fig. 2 is a view similar to that of Fig. 1 but with the valve in an intermediate position.

Fig. 3 is a similar view but with the valve in the other extreme position.

Fig. 4 is a top plan view of the valve and adjacent controlling apparatus with the valve shown in intermediate position, the other extreme positions being, however, indicated by dotted lines.

Referring now to the figures in all of which like parts are designated by like reference characters, at 1 I show the casing of a valve interposed in a gasoline feed pipe line 2 leading from a source of gasoline supply such as a vacuum storage tank to a point of gasoline consumption such as the engine 55 of the automobile.

At 3 I show a valve handle having its up-

per portion bent at right angles as shown at 4. At 5 I show the casing of a Bowden wire control which is tubular and receives a Bowden wire 6 attached at one end to an operating handle 7 and at the other end the Bowden wire 6 is bent downwardly at right angles and passes through a perforation 8 in the valve handle portion 4 and is headed over at 9 to prevent removal therefrom,—the fit of the wire 6 in the opening 8 being loose so as to permit relative rotation of the wire within the opening. At 10, I show a Bowden wire support secured at 11 on an extension 12 of the casing 1, said extension being 70 a portion of the gasoline line 2.

At 13 I provide a flexible Bowden wire directing and protecting tube secured at one end by a clamping nut 14 to the end of the tubular frame 5 and at the other end being 75 secured within an end opening thereof in the support 10 as shown at 15, the Bowden wire 6 passing from the point 8 on the valve handle 4 to the attached handle 7 passing through the support 10, the flexible tube 13 80 and the tubular frame 5, the tubular frame 5 carrying a flange 16 by which it is secured to a support such as the dash of an automobile 17.

As shown herein the above is accomplished 85 by means of screws 18. The opening 15 through the support 10 is reduced in diameter at the end 19 towards the valve handle 4, and the valve operating element 3 is adapted to rotate within the casing 1, as illustrated, on a vertical axis to permit the flow of gasoline as shown preferably at Fig. 1, and to shut off the flow of gasoline completely as shown preferably at Fig. 3. Fig. 2 does not illustrate an operative position, 95 but only a position intermediate the two extreme positions and which extreme positions may be reversed as to their functions.

By referring now particularly to Fig. 4, it will be seen that when the valve is in 100 its intermediate position, the Bowden wire 6, which is of spring material such as steel wire, is bent rather abruptly at the position 20 where it enters the support 10, but that in the two extreme positions shown in dotted lines in Fig. 4, and as illustrated in Figs. 1 and 3, as well, it will be noted that the Bowden wire is approximately straight and in axial alignment with the main portion of the Bowden wire extending between the 110 valve and the handle 7, and particularly is in axial alignment, approximately, with

the opening through the support 10 at its forward portion 19. By this arrangement, the operator will not leave the controlling handle 7 in an intermediate position, since by the resistance to his push or pull effort in advancing or retracting the handle 7, which is noticeable when the valve is near the intermediate position and the sudden release of resistance at either end of the movement, the different positions of the valve will be communicated to him. Moreover, this arrangement causes the valve to snap into either extreme position suddenly by the sudden release of resistance to the adjusting efforts of the operator.

Having thus described a particular embodiment of my invention, I am aware that numerous and extensive departures may be made therefrom but without departing from the spirit of my invention.

I claim:

1. In a valve adjusting mechanism having an extreme position and other positions, the combination with a Bowden wire for operating the valve, a valve handle for the valve and adapted to rotate the same to different operative positions, a handle for the Bowden wire, a protecting and directing

tube enclosing said wire, the end of said tube being held approximately rigid with respect to the valve and its opening being approximately in axial alignment with the point of connection of the said wire to the said handle when the handle is in its said extreme position, and out of alignment therefrom when the handle is in other positions.

2. In an adjusting mechanism for valves having a closed and open position and intermediate positions, the combination with a Bowden wire for operating the valve, a valve handle for the valve adapted to rotate the same to different operative positions, a handle for the Bowden wire, a protecting and directing tube enclosing said wire, the end of said tube being held approximately rigid with respect to the valve and its opening being approximately in axial alignment with the point of connection of the wire to the handle when the handle is in either its valve opening or valve closing positions, and out of alignment therefrom when the handle is in other positions.

In testimony whereof I hereunto affix my signature this 22 day of April, 1924.

MATTHEW MAYER.
